INSULATOR CAP

Charles S. Card, Cortland, N. Y., assignor to The
Brewer-Titchener Corporation, Cortland, N. Y.,
a corporation of New York

Application January 12, 1946, Serial No. 640,730

1 Claim. (Cl. 174—188)

1

This invention relates to an improved insulator cap and a method of making the same. More particularly my invention relates to caps for encasing and supporting insulators for electrical transmission lines.

It is an object of the present invention to provide an improved insulator cap which is inexpensive in construction and which is made of several pieces that can be readily assembled and which, when assembled, is rugged and strong, will not leak and will give satisfactory service for a long period of time.

A further object is the provision of an improved insulator cap assembled from a separately made cap body and a coupling or supporting piece and which is so designed that the same cap body may be assembled with any one of a number of different types of coupling or supporting pieces thereby simplifying both the production and storing problem.

Other objects will be apparent from the following detailed description of the drawings in which:

Fig. 1 is a top plan view of an insulator cap embodying my invention.

Fig. 2 is a sectional view on the line 2—2 of Fig. 1.

Fig. 3 is a side elevational view at right angles to Fig. 2.

Fig. 4 is an elevational view of the clevis or ear portion of the cap prior to assembly.

Fig. 5 is a sectional view of the bell portion of the cap prior to assembly and,

Figs. 6 and 7 are a top plan and side elevational views respectively of a socket member which may be used in place of the clevis or ear piece shown in Fig. 4.

My invention contemplates forming the insulator cap in a plurality of sections and thereafter assembling the sections so that the finished cap is as satisfactory in all respects as a cap made in one piece.

In the illustrated embodiment, the cap is made in two sections, namely, a cap body 10 and the supporting or coupling portion which may take the form of clevis or ear piece 11 shown in the first four figures of the drawing or the socket piece 11' shown in Figs. 6 and 7.

The cap body is generally bell shaped having a depending apron portion 12 terminating in an inwardly turned flange 13 which serves as a positive stop for gripping the cement holding the insulator body in position. The cap body turns inwardly at the top as indicated at 14 and is provided with a central aperture 15 whereby the

connecting piece is attached to the cap body. The cap body is made of a suitable metallic material and may be formed by stamping or forging.

5 Similarly, the supporting or coupling piece is made of suitable metallic material and may be either a stamping or forging. The clevis or ear piece shown in the first four figures of the drawing is a forged member and consists of a disk shaped base 16 of larger diameter than the opening 15 and adapted to rest on the top 14 of the cap body. Projecting downwardly from the disk base is a tapered coupling lug 17 which is of such a diameter that it may be inserted through 10 the opening 15 and the upper end thereof will tightly engage the sides thereof. Projecting upwardly from the disk base are a pair of spaced parallel ears or lugs 18 provided with apertures 19 whereby the insulator cap is suspended from 15 the supporting towers or poles.

20 In assembling the cap the coupling lug 17 is inserted through the aperture 15 and when fully inserted there is preferably a rigid fit between the lug and sides of the aperture. The portion 25 of the lug which projects inside of the cap body is then upset or riveted as indicated at 20 in Fig. 2. When thus assembled it will be seen that the base 16 of the ear piece rests upon and 20 tightly engages the outer surface of the top 14 of the cap body and the riveted portion 20 tightly 30 engages the inner surface thereof. The connection is of such a nature that there can be no leakage at this point and an insulator cap having all of the strength and characteristics of a 35 unit cap is provided.

The cap body 10 may be used with supporting or coupling pieces of various types and in this manner the production and storing problems are greatly simplified in that it is only necessary to 40 make and store one type of cap body. Coupling pieces of various types may be made to be assembled with the cap body. An example of a different type of coupling piece is shown in Figs. 6 and 7. Thus the coupling piece 11' is a ball and 45 socket type of member consisting of a body 21 formed with a conventional type of socket 22 extending inwardly from one side thereof. The socket is open at the top and is provided with overhanging walls as shown. An aperture 23 may 50 be provided at the closed end of the socket whereby the ball or other coupling member which is inserted in the socket may be secured in position and held against accidental displacement. Depending from the body 21 is a tapered coupling 55 lug 17' similar in structure and function to the

coupling lug 17. The ball and socket coupling piece 11' may be assembled with the insulator cap in the same manner as the clevis or ear piece 11.

In manufacturing my improved insulator cap, the cap body is made as a separate unit by stamping or forging and similarly the coupling piece is made as a separate unit. In the illustrated embodiments, the supporting or coupling pieces are forgings with the apertures and sockets machined or otherwise formed therein. Thereafter the cap is assembled as previously described thereby providing a cap which will support the insulator in a very satisfactory manner, which will not leak, and which has the strength and all of the desirable characteristics of a unitary structure. Modifications may be made in the illustrated embodiment of my invention without departing from the invention as set forth in the accompanying claim:

I claim:

An insulator cap comprising a bell shaped cap body having a depending apron portion and a dome-shaped top portion formed with a central aperture and a unitary coupling piece formed

10

15

25

with a base portion resting on the dome-shaped top portion of the cap body and covering and substantially overlying the edges of the aperture and having a solid coupling lug projecting inwardly from the base portion through and substantially filling the aperture, said lug being upset inside the cap body so as to overlap the edges of the aperture and engage the inner surface of the dome-shaped top portion.
